UNITED STATES PATENT OFFICE

EUGÈNE FIÈVET, OF LILLE, FRANCE

PREPARING MACHINE FOR SPINNING

Application filed December 11, 1928, Serial No. 325,322, and in Great Britain December 22, 1927.

This invention relates to "preparing appliances" for the materials used in spinning and particularly to machines for preparing flax, hemp, jute and the like and of the type 5 wherein "fallers" are employed such for example as in spreaders, drawers, roving machines and others.

In connection with this class of machines it is well known that the combs or gills together 10 with the fallers equipped therewith require to be cleaned as often as possible as the nature of the yarn depends upon their condition and ordinarily such cleaning is effected in place by means of hooks formed from a sort of knife 15 blade bent upwards with which the dust which accumulates longways along the faller is withdrawn from the gills more or less rapidly according to the pitch and the nature of the material being treated.

These hooks operate satisfactorily but require considerable skill and dexterity to avoid the risk of breaking, bending, chafing or twisting the points of the pins and the great care required constitutes an objection. Another 25 objection consists in the fact that in order to clean the gills, it is necessary to stop the machines for a considerable time.

To remedy the drawbacks of hand cleaning, it has been proposed to clean the fallers and 30 gills without manual labour or stoppage of the frames by means of a series of brushes applied in such a way that the fallers deposit in the hairs of the brush, the pieces of wood and straw with which they may be laden and the 35 down left by any one faller is removed by the succeeding faller. The arrangement is, however, quickly rendered inefficient as the bars in dropping bend back the hairs of the brush so that the extremities of the pins escape the 40 brush action—moreover, the rapid wear of the brush progressively increases the inefficiency.

The object of the present invention is to 45 overcome the foregoing difficulties and to provide an automatic cleaning device which remains completely efficient and cleans the fallers and gills without becoming dirty itself, the actual cleaning means being subject to little wear, simple, easily interchangeable and 50 of a low cost.

The invention consists in a method of 55 cleaning the gill bars and gills of preparing appliances of the kind indicated according to which cleaning means is inserted between a drawing roller and a dropping or disengaging faller in such a manner that the dropping or like movement of the faller brings both the bar and gills into contact with the cleaning means which removes the impurities therefrom.

The invention further consists in cleaning 60 means for operating in accordance with the preceding paragraph comprising a resilient element arranged to contact with a drawing roller at a region prior to its contact with the sliver or ribbon and to be compressed by a faller and its pins during their movement of retirement from the said sliver or the like.

The invention further consists in a device 65 in accordance with the preceding paragraph comprising a transversely disposed member formed of resilient material such as rubber which may take the form of a hollow cylindrical tube long enough to contact with all that part of the faller which is to be cleaned, 70 said member being preferably supported upon a wire or rod passing in an axial direction therethrough.

The invention further consists in a device 75 in accordance with the preceding paragraph in which the cleaning member is supported upon a wire in the form of a stirrup mounted with pivotal joints on the sides of the conductors.

The invention also consists in improvements in or relating to preparing machines for spinning as hereinafter described.

Referring now to the accompanying more or less diagrammatic drawings which show by way of example one way of carrying the 80 invention into effect:

Figure 1 is a side elevation of a train of 85 rollers of a second drawing frame with an embodiment of the invention applied thereto;

Figure 2 is a front elevation of the arrangement shown in Figure 1, fallers and gills omitted;

Figures 3, 4 and 5 are fragmental views 90 showing successive positions of the devices shown in Figure 1.

The method according to this invention is characterized by the selection of the position of the cleaning means as well as by the arrangement and construction of the same, the cleaning means being preferably placed resting directly and freely in contact with the drawing roller at any convenient position between the slivers or ribbons drawn by the gills and the horizontal plane passing through the axis of the said roller, preferably immediately below the conductors, and comprising a tubular member of suitable dimensions which may vary according to the diameter of the roller and the dimensions of the gills and of a length corresponding to the portion of the faller to be cleaned. The material from which this member is formed is preferably yielding, flexible and pliant such as for example rubber so that it may be compressed and altered in shape between the drawing roller and the faller at the moment that the latter drops and after their passing has been effected the member may, owing to its elasticity, recover to a certain extent its original shape coming then into light contact with the gills or combs, the complete original shape of the elastic member being fully recovered when the faller has almost reached its lower path.

Such a cleaning member operates automatically and with constant efficiency due to the fact that the elastic member is capable of being compressed in the very restricted space in which it is placed and the fallers are obliged to rub against it during their fall as well as the points of the combs or gills along their total length. There is, therefore, no formation of down and the fibres hooked on to the points of the pins cannot remain there but are immediately returned to the slivers or ribbons which pass close above. Periodical cleanings are, therefore, no longer necessary.

The cleaning member in the convenient embodiment illustrated in the accompanying drawings is made from a simple rubber tube of suitable dimensions having a smooth or other surface which may be fluted if desired or be fitted with projections of any form; its length corresponds to the width of each upper pressing roller or to that of the gills thus forming an individual cleaning means for each gill. Alternatively it may correspond to the length of the drawing roller usually in one piece and thus constitute a cleaning means common to all the gills.

The member is positioned immediately below the conductors of each sliver corresponding to the number of pressing rollers and it is supported relative to the drawing roller by a steel wire in the form of a stirrup passed loosely into the rubber tube and held to revolve freely by the ends which are placed in the sides of the conductors.

In the convenient embodiment shown in Figures 1 and 2 there is provided a drawing roller 1 with its rubber 2 and an upper press-

ing roller 3, usually of elm wood, together with the metal piece 4 usually called a "conductor" for guiding the ribbon or strand 5 coming from the drafting of the fallers between the rollers 1 and 3 to undergo a final drafting prior to being led in the form of sliver to the doubling plate 6. Close to the drawing roller is the last faller 7 with its gills or combs 8 which is dropped from the upper slide to the lower slide to be led back by the bottom screws.

Immediately below each conductor 4 is a cleaning member consisting of a rubber tube 9 of a sufficient thickness and of a length corresponding to the width of the conductor 4 or to that of the gills resting freely on the drawing roller 1 and of such a diameter that when the faller 7 reaches approximately the end of the course the said tube is in tangential contact with the roller as well as with the front of the faller as shown in Figure 1 without being pressed out of shape or compressed in any way.

For maintaining the free position of the aforesaid rubber tube 9 a wire 10 is passed through it in an axial direction. This wire is bent in the form of a stirrup having sides 11 and is mounted so as to oscillate freely about its ends 12 which are fixed in holes provided in the sides of the conductor 4; the tube 9 being thus hung freely upon the wire 10 can revolve by friction.

The foregoing arrangement of the cleaning member 9 may be the same in a case where a rubber tube is in one piece and common to all conductors and a practically similar attachment may be provided.

The working of the cleaner member 9 just described is illustrated by figures 3, 4 and 5 and as shown in Figure 3 when the upper faller 7 having completed its course is stopped and constrained by the cams to drop on to the lower slide, the cleaning member 9 is appreciably compressed owing to the fact that it is squeezed between the drawing roller 1 and the front of the faller 7 which is descending and in so doing draws it round pressing it more and more out of shape; this drawing round is, however, controlled by the cleaning member 9 being mounted on the wire 10. When the pins of the gills 8 reach the level of tube 9 as the faller drops the tube is somewhat less compressed recovering almost its original shape as shown in Figure 4 yet still being slightly distorted at its point of contact with the pins which are thereby slightly rubbed along their length from the base to the points, the elastic tube 9 recovering its original shape immediately the points of the gills 8 have freed it. The operation is the same for each successively dropping faller thus assuring automatic and efficient cleaning of the fallers and gills.

It is to be understood that changes and modifications and improvements may be ap-

plied according to the nature of the preparing machine using fallers to which this new kind of automatic cleaner may be applied and the use of any cleaning means at the position indicated may be adopted without departing from the spirit of the present invention.

5 What I claim is:

1. In preparing devices of the character described, in combination, a drawing roller, a dropping faller including a bar and gills, and cleaning means positioned tangentially of the upper face of the roller adjacent the faller in such manner that during dropping 15 movement of the faller both the bar and gills thereof contact with the cleaning means so that the impurities are removed from the faller.

2. A device as claimed in claim 1, wherein 20 the cleaning means consists of a resilient element which is adapted to be partially compressed by the faller.

3. A device as claimed in claim 1, wherein 25 the cleaning means consists of a transversely disposed resilient member in the form of a hollow cylindrical tube of a length corresponding to that part of the width of the faller which is to be cleaned.

4. A device as claimed in claim 1, wherein 30 the cleaning means is in the form of a hollow cylindrical tube-like resilient member, and a pivotally mounted stirrup having its medial portion acting to revolvably support the member.

35 In testimony whereof I affix my signature.

EUGÈNE FIÉVET.
